(57) **CLAIM**

The ornamental design for a window visor for vehicle, as shown and described.

DESCRIPTION

FIG. 1 is a side perspective view of a first embodiment of a window visor for vehicle for a driver side window showing my new design;

FIG. 2 is a front view of the first embodiment of a window visor for vehicle for the driver side window;

FIG. 3 is a back view of a first embodiment of the window visor for vehicle for the driver side window;

FIG. 4 is a right side view of the first embodiment of a window visor for vehicle for the driver side window;

FIG. 5 is a left side view of the first embodiment of a window visor for vehicle for the driver side window;

FIG. 6 is a top view of the first embodiment of a window visor for vehicle for the driver side window;

FIG. 7 is a bottom view of the first embodiment of a window visor for vehicle for the driver side window;

FIG. 8 is a side perspective view of the second embodiment of a window visor for vehicle for a passenger side window;

FIG. 9 is a front view of the second embodiment of a window visor for vehicle for the passenger driver side window;

FIG. 10 is a back view of the second embodiment of a window visor for vehicle for the passenger side window;

FIG. 11 is a right side view of the second embodiment of a window visor for vehicle for the passenger side window;

FIG. 12 is a left side view of the second embodiment of a window visor for vehicle for the passenger side window;

FIG. 13 is a top view of the second embodiment of a window visor for vehicle for the passenger side window; and,

FIG. 14 is a bottom view of the second embodiment of a window visor for vehicle for the passenger side window.

Right side views not shown are mirror images of left side views. Any broken lines illustrative of environmental structure in the drawings are not part of the design sought to be patented.
